UNITED STATES PATENT OFFICE.

GEORGE H. DUNHAM, OF TRINIDAD, COLORADO.

COMBINATION BRUSH AND COMB.

1,127,746.

Specification of Letters Patent.

Patented Feb. 9, 1915.

Application filed June 28, 1913. Serial No. 776,275.

To all whom it may concern:

Be it known that I, GEORGE H. DUNHAM, a citizen of the United States, residing at Trinidad, in the county of Las Animas, 5 State of Colorado, have invented certain new and useful Improvements in Combination Brushes and Combs; and I do hereby declare the following to be a full, clear, and exact description of the invention, such as 10 will enable others skilled in the art to which it appertains to make and use the same.

The present invention is directed to improvements in combination brushes and combs, and has for its object to so construct 15 a device of this character that the body thereof forms a receptacle for the comb.

A further object of the invention is to combine with a toilet article of this type a mirror so that a number of toilet requisites 20 are always at hand.

A still further object of the invention is to so construct an article of this type which is exceedingly simple in construction, and neat in appearance.

With these and other objects in view, this 25 invention resides in the novel features of construction, formation, combination and arrangement of parts to be hereinafter more fully described, claimed and illustrated in 30 the accompanying drawing, in which:—

Figure 1 is a plan view of the device. Fig. 2 is a similar view with the back removed and showing the comb in its inoperative position. Fig. 3 is a similar view showing 35 the comb in its operative position. Fig. 4 is a sectional view on line 4—4 of Fig. 1. Fig. 5 is a similar view on line 5—5 of Fig. 1. Fig. 6 is a detail perspective view of one 40 of the leaf springs. Fig. 7 is a detail sectional view of a modified form of the button. Fig. 8 is a horizontal sectional view on the line 8—8 of Fig. 7.

Referring to the drawing, the numeral 1 designates the head of the brush which is 45 formed from sections 2 and 3 which have formed integral therewith handle sections 4 and 5, the section 3 having secured to its under surface the usual bristles 6. The section 3 is provided with a recess 7, the same 50 being disposed horizontally in the section with the entrance to said recess positioned at one of the side edges thereof. Slidably mounted in the recess 7 is a comb 8, the same being provided with spaced ears 9, said ears 55 having their outer edges provided with metallic strips 10 which carry pins 11. Connected

to the end walls of the recess 7 are the outer ends of the leaf springs 12, which are provided with alined perforations 13 which are adapted to be engaged by the pins 11 to hold 60 the comb in its inoperative or operative position. Formed in the base of the recess 7 is a longitudinal groove 15 in which operates the rod 16, which has its inner end curved, as at 17, and disposed in the socket 18 formed in the sections 2 and 3, the sleeve 19 being fixed in said socket. The outer end of the rod 16 is pivotally connected to one of the leaf springs 12. The base of the recess 7 is also provided with a groove 20 arranged 65 parallel with the groove 15. Operating in the groove 20 is a link 21, the inner end of which is pivotally connected to the innermost spring 12, while the outer end is similarly connected to one end of the bar 22, 70 said bar being pivotally mounted in the recess and having its other end pivotally connected intermediate the ends of the rod 16. Mounted in the recess 7 is a bow spring 23, the ends of which are in engagement with 75 the eyes 24 carried by the ears 9 of the comb so as to automatically project the comb from the recess 7 to its operative position upon flexing of the leaf spring 12.

The section 2 of the head 1 of the brush 85 is provided with a guideway 25 and in which is engaged the mirror 26 which may be conveniently removed when the brush or comb is in use.

Operating in the sleeve 19 is a button 27, 90 the same having the tapered bore formed therein for engaging the curved end of the rod 16, whereby when the button is forced inwardly, the rod 16 may be operated in the manner to rock the bar 22, thus causing the 95 link 21 to operate simultaneously with the rod to force the leaf springs 12 in opposite directions, which action disengages the pins 11 from the perforations 13, whereby the spring 23 forces the comb outwardly, the movement of said comb being arrested upon the pins 11 engaging the perforations 14, thereby causing the comb to be positioned in its operative position. To return the comb to its inoperative position, it is only necessary to force the same into the recess 7, whereupon the pins 11 will snap into engagement with the perforations 13 of the leaf springs 12.

The section 2 is secured to the section 3 in 110 a well known manner, thus closing the recess 7 and inclosing the operative parts of

the device. It is obvious that the sections 3 and 2 can be conveniently separated so as to replace any broken parts of the device.

In Fig. 7 the rod 16 is provided with an eye 28 which is positioned in the socket 29 for engagement by the tapered button 30, the lower end of which is connected to the base of the socket by a coil spring 31, the tendency of which is to normally force the button partially from engagement in the socket 28. It is obvious that when pressure is applied to the button 30 that the rod 16 will operate in the manner hereinbefore described.

15 What is claimed is:—

1. A device of the class described comprising a head having a rectangular recess formed therein, leaf springs having their outer ends secured upon the end walls of 20 said recess and provided adjacent their inwardly curved free ends with perforations, a comb slidable within said recess, pins secured upon the ends of said comb and normally engaging said perforations for retaining said comb in its retracted position, a spring within said recess for urging said comb outwardly, and means for forcing the free ends of said springs apart for disengaging them from said pins.

30 2. A device of the class described comprising a head having a rectangular recess therein, a comb slidable within said recess, a spring for urging said comb outwardly, means for retaining said comb in its re- 35 tracted or protracted position, said means comprising leaf springs having their outer ends secured to the end walls of said recess, provided adjacent their inwardly curved free ends with perforations and further pro-

vided intermediate their ends with other 40 perforations, pins on the ends of said comb adapted to engage said first named perforations for retaining said comb in its retracted position and adapted to engage said last named perforations for retaining 45 said comb in its protracted position, and means for moving said leaf springs outwardly for disengaging them from said pins.

3. A device of the class described comprising a head having a rectangular recess formed therein and a socket adjacent said recess, leaf springs having their outer ends connected to the end walls of the recess and their free ends provided with perforations, 50 a bar rotatably mounted in said recess, a rod operable in said recess and having one end connected with one of said leaf springs and its other end disposed in said socket, said bar having one of its ends connected with 55 said rod, a link having one end connected with the other of said leaf springs and its other end to said bar, and means operable in said socket engaging said other end of said rod, a comb slidable in said recess and provided with pins arranged to engage said perforations when the comb is retracted and thereby hold the same from protraction, 60 said springs being disengaged from said pins by movement of said rod, bar and link, 65 and spring means urging said comb into protracted position.

In testimony whereof, I affix my signature, in the presence of two witnesses.

GEORGE H. DUNHAM.

Witnesses:

SADIE RATHKEY,
JAS. HANLEY.
